UNITED STATES PATENT OFFICE

OSWALD D. VON MEHREN, OF NEW YORK, N. Y., ASSIGNOR TO MEHREN LOCK CO., INC.,
OF CLIFTON, NEW JERSEY, A CORPORATION OF NEW JERSEY

KEY

Application filed February 26, 1929, Serial No. 342,723. Renewed July 26, 1932.

This invention relates to keys for changeable combination locks, the object of the invention being to provide a simple and efficient key construction for use in conjunction with such locks.

Locks of the character under consideration are adapted to be operated by a suitable key, which when thrust into the keyhole of the lock barrel serves, through such operation, to act upon relatively movable pins or rods in order to so relatively longitudinally position them as to unlock the barrel for rotation. The relative positions of the several pins or rods determine the locked or unlocked condition of the barrel.

My prior application, Serial No. 276,765 discloses a novel form of lock of the character under consideration and provides for change of combination by authorized persons. The present application, which is directed to the key for cooperation with such a lock, forms a continuation in part of my said pending application.

One important object of the present invention is to provide a key embodying rod or pin operating devices which are relatively adjustable, so that they will severally act upon the pins or rods in a predetermined manner to simultaneously adjust all of the pins or rods to the relative positions required for any particular combination and to so constitute a key that it will be simple in construction and thoroughly efficient in the performance of its intended functions.

In practically carrying out the invention, the key is provided with a suitable shank having an appropriate handle portion. The shank is formed with longitudinal passages in which are positioned longitudinally adjustable plungers adapted to engage and operate the pins or rods of the lock when the key is introduced into the keyhole. These plungers are adapted for longitudinal adjustment into various relative positions in order to effect different combinations, and means is provided for locking the plungers in any of the many positions of which they are susceptible, so that after said plungers have been adjusted in predetermined position, they may be locked in such position against inadvertent

shifting until such time as it is desired to effect a change in combination.

An important feature of the invention in its preferred form is that the plungers to which I have referred are mounted wholly within the slots or slides in which they are guided so that said plungers are supported in more or less enclosed condition throughout their entire length. As a result they cannot be bent if the key is dropped or struck against some unyielding obstruction, but will retain the straight effective condition indefinitely.

Another important practical feature consists in so forming the handle of the key that at least a portion of such handle is movable into and out of position to cover and conceal the adjusting devices for such plungers and serve in effect as a lock or shield which, under ordinary conditions, will preclude tampering with the combination of the key.

I am aware that keys have heretofore been used having longitudinal adjustable slides and analogous devices for operating the movable parts of a lock, but in none of these prior constructions have the features to which I have referred found practical embodiment.

The present invention, therefore, consists in marked practical improvements in key construction with the result that a key is produced capable of efficient operation of such locks as I have hereinbefore referred to.

Features of the invention, other than those referred to, will be apparent from the hereinafter detailed description and claims, when read in conjunction with the accompanying drawings.

The accompanying drawings illustrate different practical embodiments of the invention, but the constructions therein shown are to be understood as illustrative, only, and not as defining the limits of the invention.

Figure 1 is a side elevation of one form of key embodying the present invention.

Figures 2, 3 and 4 are, respectively, sections on the lines 2-2, 3-3 and 4-4 of Figure 1.

Figure 5 is a detailed elevation of one key pin or plunger used in the construction of Figures 1 to 6.

Figure 6 is a face view of the key of Figure 1 with the cover removed.

Figure 7 is a face view of a modified form of key with the cover removed.

5 Figure 8 is a like view of the key of Figure 7 with the cover closed.

Figure 9 is a section on the line 9—9 of Figure 7.

10 Figure 10 is a section on the line 10—10 of Figure 8.

Figure 11 is a side elevation of one of the pins or plungers shown in the key of Figure 7.

15 Figure 12 is a side elevation of a further modified form of key.

Figure 13 is a section on the line 13—13 of Figure 12.

20 Referring first to Figures 1 to 6, the key therein is made in the form of a flat blank of material comprising a shank 101 and a handle 102. The key is of the general character of a conventional flat key although slightly thicker. Adjacent the opposite face of the blank, holes are bored extending longitudinally of the shank and from the free end thereof. These holes are parallel to one another and preferably so close to the facial surfaces of the key that they will cut through the faces of the blank.

25 30 Six such holes are bored and they are disposed in the same relative relation as the lock pins or rods with which they are adapted to cooperate. In each of the holes is introduced a pin or plunger 103 and each plunger has a cut away portion 104 provided at the rear end of the pin with an upturned or hook shaped toe 105.

35 The opposite faces of the handle 102 are provided with dove tail slots 106 and in each 40 of these dove tail slots is positioned a sliding plate 107, the inner face of which is grooved to provide a number of parallel grooves 108 extending across axially of the key and spaced closely apart.

45 50 If the key is to be used with a construction such as disclosed in my copending application aforesaid, the space between the grooves 108 will be equal to the thickness of one of the lock disks. The shank of the key is graduated by lines 109 spaced apart equal to the distance between centers of the grooves 108. Thus the pins 103 are adapted to be adjusted longitudinally in the shank of the key when the parts are as shown in Figure 55 6 to adjust the pins to the desired combination by reference to the graduations 109 and if the slides 107 are thereupon slid longitudinally into the position of Figures 1 and 3, the toes 105 of the respective plungers 103, 60 will engage with appropriate grooves 108 on the slides 107, and the plungers will be thereby locked in position against inadvertent longitudinal shifting so long as the plates are in their closed positions exhibited 65 in Figure 1. The plates are normally se-

cured in these closed positions by means of screws 110.

A notch 111 is preferably formed in the shank of the key to cooperate with the front plate of the lock in such manner as to preclude removal of the key in positions other than those predetermined.

In the construction of Figs. 7 to 11, the body of the key is formed with a shank 101^a and a handle 102^a. The key blank is provided with longitudinally parallel grooves 112 which are undercut or dove tail as shown. In each of these grooves is a plunger 103^a of corresponding cross section. Each plunger has a serrated edge 105^a and with the 80 serrated edges of each two plungers a leaf spring 108^a is adapted to cooperate. The leaf springs are secured in place by rivets 113 and the free end of each of these leaf springs is provided with a turned down nose 85 adapted to simultaneously engage with the serrated edges 105^a of the two associated plungers to lock the plungers against inadvertent longitudinal movement.

When it is desired to change the adjustment of the plungers, the leaf spring is drawn outwardly to release the plungers for adjustment, and after the adjustments have been made with the assistance of scales 109^a, the springs are released and sprung back into engagement with the plungers to lock them in position. The opposite faces of the blank are flush and with these faces of the handle portion are adapted to cooperate cover plates 107^a, one of which is positioned at each face of the blank. Both the cover plates are mounted for pivotal movement on a rivet 106^a and are secured together for simultaneous pivotal movement by an interposed abutment 114, the inner face of which is curved at 115 on a radius, the center of which is the axis of the rivet 106^a.

The corresponding end of the handle is also curved as at 116 on the same radius so that the cover plates may be swung from the position shown in Figure 7 to the position shown in Figure 8 and vice versa. When in position as shown in Figure 7, the plungers may be readily adjusted, but when in the position of Figure 8, the cover plates conceal the adjusting devices in the key. The cover plates may be locked in the position shown in Figure 8 by a screw 110^a. The key blank is preferably provided with a key chain hole 117 and the cover plates are preferably so formed as to provide perforations 118 to register with the perforations 117 when the parts are in the position of Figure 8. When the key as shown in Figure 8 is positioned on a key ring, the ring will pass through the aligned perforations of the handle and cover plates and will hold the cover plates in closed position even though the screw 110^a is not secured in place. This is advantageous since it precludes changing of the key combina- 130

tion without removal of the key from the key ring and this minimizes the opportunity for tampering with the key by unauthorized persons.

5 In the structure of Figures 12 and 13, an unadjustable key is shown. With this arrangement, the combination cannot be changed without making a new key because with this arrangement the shank 101b is provided therein with pockets 119, the bases of which form abutments 120 to engage with the key operated pins or rods of the lock.

10 The advantage of the structure of Figures 12 and 13 over some of the keys heretofore employed is its marked simplicity and the further fact that dirt or extraneous matter cannot get into the holes or pockets and clog them nor are there any projecting parts which may be readily bent and thus rendered 15 inoperative to actuate the lock. In all of the adjustable forms of key which I have shown, the plungers for operating the lock pins into predetermined relative positions are supported throughout their entire lengths in slots or 20 holes formed in the key blank. This is of very considerable importance because I have found in practice that where keys are provided with plungers which extend beyond the end of the shank or handle, as in the majority of cases, these pins will, after a relatively short time, become bent or distorted 25 because they must of necessity be made quite small and relatively weak structurally.

30 With the present invention, in contradistinction, the plungers may be made even smaller than heretofore and a greater number of them may be grouped on a key of relatively small size and yet by supporting them throughout their entire length, the possibility of damage to the plungers is practically 35 nil. In all of the structures which I have shown and described, moreover, the slots in which the plungers are mounted for adjustment are open to the sides of the key, so 40 that dirt or other extraneous matter cannot accumulate therein or preclude function of the key in a proper manner.

45 The arrangement in each instance is such as to permit the use of a key of relatively small size and in the adjustable combination keys, the key need be little if any larger than conventional lock keys as now employed. The ability to adjust a key in the manner which I have described and to normally cover 50 and conceal the adjustable devices associated therewith in a manner to safeguard the same from tampering, is, so far as I am aware, highly novel.

55 The arrangement described is of marked practical importance for it enables a key holder to change the combination of the lock at will without necessity of employment of a different key, it being only necessary to manipulate the lock in the manner required and to thereupon change the key

accordingly. This change may be manifestly accomplished without the use of tools, any implement which will release the screws 110 or 110a being appropriate to permit of access to the adjustable devices of the key.

70 The accompanying drawings are illustrative of the invention in its preferred practical form, but the invention is to be understood as fully commensurate with the appended claims.

75 Having thus fully described the invention, what I claim as new and desire to secure by Letters Patent is:

1. A combination lock key embodying a blank having shank and handle portions, lock operating plungers extending longitudinally of the shank and parallel to one another and housed wholly within the confines of the blank to be supported for their entire lengths at all times, said plungers being mounted 80 for longitudinal adjustment relative to the shank and each other, and means for locking all of the rods against inadvertent movement.

2. A combination lock key embodying a blank having shank and handle portions, lock operating plungers extending longitudinally of the shank and parallel to one another and housed wholly within the confines of the blank to be supported for their entire 95 lengths at all times, said plungers being mounted for longitudinal adjustment relative to the shank and each other, means for locking all of the rods against inadvertent movement, and means for securing the 100 plunger locking means against inadvertent release of the plungers.

3. A combination lock key embodying a blank having shank and handle portions, lock operating plungers extending longitudinally of the shank and parallel to one another and housed wholly within the confines of the blank to be supported for their entire lengths at all times, said plungers being mounted for 105 longitudinal adjustment relative to the shank and each other, means for locking all of the plungers against inadvertent movement, and a graduated scale formed on the blank adjacent the plungers to facilitate positioning 110 of the plungers according to a predetermined combination when said plungers are released for adjustment.

4. A combination lock key embodying a blank provided with shank and handle portions, the shank portion having a plurality of passages extending from the free end of the shank in parallel relation to one another and with one side of each passage open for 120 its entire length to one face of the blank, lock 125 operating plungers positioned in and longitudinally adjustable with respect to said passages said plungers being supported for their full lengths by the walls of the passages at all times, and means for locking said plung- 130

ers against inadvertent longitudinal movement.

5. A combination lock key embodying a blank provided with shank and handle portions, the shank portion having a plurality of passages extending from the free end of the shank in parallel relation to one another and with one side of each passage open for its entire length to one face of the blank, lock 10 operating plungers positioned in and longitudinally adjustable with respect to said passages said plungers being supported for their full lengths by the walls of the passages at all times, means for locking said plungers against inadvertent longitudinal movement, and means for securing a plunger locking means against inadvertent release of the plungers.

6. A combination lock key embodying a blank provided with shank and handle portions, the shank portion having a plurality of passages extending from the free end thereof into the handle portion, plungers positioned within the passages and adjustable longitudinally thereof, said passages being open to one face of the blank at least in the handle portion thereof to permit access to the plungers for longitudinal adjustment, and a cover normally overlying the exposed 30 portions of the plungers at the handle portion of the key.

7. A combination lock key embodying a blank provided with shank and handle portions, the shank portion having a plurality of passages extending from the free end thereof into the handle portion, plungers positioned within the passages and adjustable longitudinally thereof, said passages being open to one face of the blank at least in the handle portion thereof to permit access to the plungers for longitudinal adjustment, a cover normally overlying the exposed portions of the plungers at the handle portion of the key, and means for securing the cover in 45 closed position.

8. A combination lock key embodying a blank provided with shank and handle portions and having a plurality of passages extending from the free end of the shank into the handle portion, one side of each of the passages being open to the adjacent face of the blank, lock operating plungers positioned in and adjustable longitudinally of said passages, and means associated with the handle 55 of the blank to lock the plungers against inadvertent shifting.

9. A combination lock key embodying a blank provided with shank and handle portions and having a plurality of passages extending from the free end of the shank into the handle portion, one side of each of the passages being open to the adjacent face of the blank, lock operating plungers positioned in and adjustable longitudinally of 65 said passages, and unitary means for lock-

ing a plurality of said plungers against inadvertent longitudinal movement.

10. A combination lock key embodying a blank provided with shank and handle portions and having a plurality of passages extending from the free end of the shank into the handle portion, one side of each of the passages being open to the adjacent face of the blank, lock operating plungers positioned in and adjustable longitudinally of 75 said passages, cover plates movable with respect to the handle portion and adapted to be moved from open to closed position and vice versa, to permit access to the ends of the plungers which extend into the handle portion.

11. A combination lock key embodying a blank provided with shank and handle portions and having a plurality of passages extending from the free end of the shank into the handle portion, one side of each of the passages being open to the adjacent face of the blank, lock operating plungers positioned in and adjustable longitudinally of 85 said passages, cover plates movable with respect to the handle portion and adapted to be moved from open to closed position and vice versa, to permit access to the ends of the plungers which extend into the handle portion, and graduated scales associated 90 with the handle portion of the passages to facilitate adjustment of the plungers to predetermined combinations.

12. A combination lock key embodying a blank provided with shank and handle portions and having a plurality of passages extending from the free end of the shank into the handle portion, one side of each of the passages being open to the adjacent face of the blank, lock operating plungers positioned in and adjustable longitudinally of 100 said passages, cover plates movable with respect to the handle portion and adapted to be moved from open to closed position and vice versa, to permit access to the ends of the 105 plungers which extend into the handle portion, graduated scales associated with the handle portion of the passages to facilitate adjustment of the plungers to predetermined combinations, and means for securing the 110 cover plates in normally closed position.

13. A combination lock key embodying a flat blank provided in at least one face thereof with parallel channels all of which extend from one end of the blank, lock operating plungers longitudinally adjustable within said channels, and means to lock the plungers in various positions of adjustment, said plungers being of such length that they will not extend beyond the said end of the 125 blank, in any of such positions of adjustment.

14. A combination lock key having a shank from the free end of which extends a plurality of parallel passages adapted to receive 130

the operating pins of a lock when the key is brought into cooperative relation thereto one side of each passage being cut away to the adjacent face of the shank to preclude lodging of extraneous matter in the passages.

15. A combination lock key having a shank from the free end of which extends a plurality of parallel passages adapted to receive the operating pins of a lock when the key is brought into cooperative relation thereto, one side of each passage being cut away to the adjacent face of the shank to preclude lodging of extraneous matter in the passages, and an adjustable member in each passage to regulate the depth thereof to the desired combination.

In testimony whereof I have signed the foregoing specification.
